UNITED STATES PATENT OFFICE.

SAMUEL V. REEVES, OF HADDONFIELD, NEW JERSEY.

STOVE.

1,255,227.

Specification of Letters Patent.

Patented Feb. 5, 1918.

Application filed July 22, 1914. Serial No. 852,349.

To all whom it may concern:

Be it known that I, SAMUEL V. REEVES, a citizen of the United States, residing at Haddonfield, county of Camden, State of New Jersey, have invented a new and useful Stove, of which the following is a specification.

My present invention consists of a novel construction of a stove, wherein a single set of castings are constructed in a novel manner, whereby either a right or left hand arrangement of the oven, the ash-pit and the fire-pot or chamber may be obtained.

It further consists of a novel construction of a front plate or casting, adapted to carry the oven door, the ash-pit door and the fire-pot door, and which is constructed in such a manner that it may be bodily reversed without any disarrangement of the doors or any change in the construction to provide for either a right or left hand arrangement of the parts.

It further consists of a novel stove, wherein a novel division plate is employed.

It further consists of a novel stove, wherein a portion of the side wall thereof is formed by a novel construction and arrangement of water back or water front.

For the purpose of illustrating my invention, I have shown in the accompanying drawings, one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities, as herein shown and described.

Figure 1 represents a front elevation of a right hand oven arrangement of a stove embodying my invention, the support therefor having been removed.

Fig. 2 represents a front elevation of my novel stove, showing a left hand oven arrangement of the parts thereof.

Fig. 3 represents a front elevation of the front plate of the stove, in detached position.

Fig. 4 represents a sectional elevation of my device.

Fig. 5 represents a section on line *a—a* of Fig. 3.

Fig. 6 represents a section on line *b—b* 55 of Fig. 3.

Fig. 7 represents a section on line *c—c* of Fig. 1.

Fig. 8 represents a section on line *d—d* 60 of Fig. 7.

Fig. 9 represents a section on line *e—e* of Fig. 8.

Fig. 10 represents a front elevation of a shank plate, in detached position.

Fig. 11 represents a section on line *f—f* 65 of Fig. 10.

Fig. 12 represents, in side elevation, a left hand oven arrangement of a dust damper and its adjuncts.

Fig. 13 represents a section on line *g—g* 70 of Fig. 12.

Fig. 14 represents an elevation of the fire end of the stove.

Fig. 15 represents a top plan view of the water jacket, in detached position.

Fig. 16 represents a sectional view of a door.

Similar numerals of reference indicate corresponding parts in the figures.

Referring to the drawings:— 80

1 designates the bottom plate of a stove embodying my invention, and which, as best seen in Fig. 4, is adapted to support the side plates 2 and 3, the front plate 4, and the rear plate 5. 6 designates the top plate, 85 the parts of which are constructed in such a manner that they may be employed with either a right or left hand arrangement of the parts thereof. The front plate 4, as best seen in Fig. 3, is provided with an 90 opening 7, on one side of which is located the lugs 8, to which the oven door 9 is hinged. The side of the door opposite the hinged portion is provided with a tongue 10 having an aperture 11 therethrough, 95 with the walls of which, the catch 12, integral with the plate 4, is adapted to interlock. The catch 12 comprises a lug having a head at its outer end, so that it will interlock with the walls of the aperture 11 of 100 the door 9, when the parts are arranged, as seen in Fig. 1, which is a right hand arrangement of the oven and its adjuncts, and also when the parts are arranged, as seen in

Fig. 2, which is a left hand arrangement of the oven and its adjuncts. I provide above and below the opening 7, rectangular or other shaped openings 13, through which 5 the soot is removed, and each of which is constructed in the same manner, and I have therefore identified the same by the same reference characters. On opposite sides of the opening 13, are the hooks or catches 14, 10 and the apertures 15, whereby plates 16 may be secured to the plate 4 by fastening devices 17 of any desired type. The front plate 4 is provided with an aperture 18 there-through, through which is adapted to pass the rod 19 of a damper 20, which latter provides for the free passage of the products of combustion from the fire chamber 21 to the chimney or smoke-pipe 22, and which when closed, will cause the heat to circulate 15 around the baffle or flue plate 23, in order to heat the oven 24 in the usual manner. The front plate 4 is provided with a rectangular shaped opening 25, see Fig. 3, and the front plate 4, above and below such opening, is outwardly deflected and rounded, as at 26 and 27. Centrally of said opening, the side walls thereof are inwardly deflected or depressed, as at 28, and provided with slots 29 and apertures 30, the slots 29 adapting the same to receive the flanges 31, 20 see Fig 4, when it is desired to slide the grate 32 into position.

33 designates a shank plate having side flanges 34 on opposite sides thereof, which 35 are adapted to be seated on the depressed portions 28 of the front plate 4 and are provided with apertures 35, whereby said shank plate 33 may be secured with respect to the front plate by means of fastening devices 40 36 of any desired type. The shank plate 33 has its side wall outwardly bulged or rounded, and said wall merges into the top portion, which is inclined inwardly, as at 37, as will be best understood by reference to 45 Figs. 10 and 11. The plate or casting 33 is provided with the bracket 38, which is apertured to form a journal for the shaker-bar or shank of the grate, it being understood that the grate members are connected 50 together, in order to provide a shaking grate, and the end of the portion of the grate mechanism which is adapted to receive the shaker bar extends in proximity to the aperture of said bracket 38, as will be understood 55 by reference to Figs. 1 and 2. In some cases the shank of the grate extends through the aperture of the bracket 38 while in other cases the hub of the shaker is received in such aperture. The portion 26 of the front plate 4 is provided with a rib 39 and the portion 27 of the front plate is provided with a rib 40, while the separating or division plate 33 is provided with an upper rib 41 and a lower rib 42, in order that the

upper door 43 and the lower door 44 will 65 form a proper joint or fit with the adjacent parts of the stove. When the parts are arranged for a right hand arrangement of the oven, the door 44 forms the ash-pit door, and when a left hand arrangement is provided for, the door 44 forms the fire door. The same is true of the door 43, it being seen that with a right hand arrangement it forms the fire door, while with a left hand arrangement, it forms the ash-pit door. The 70 door 43 is hinged to the lug 45 in any desired manner, and is provided with a catch 46 having the same conformation on its top as on its bottom, whereby it will interlock with the top or bottom wall of the aperture 75 80 89. The door 44 is mounted in a similar manner to the door 43 and is hinged to a lug 47 and provided with a catch 48 corresponding in construction to the catch 46 and adapted to interlock with the top or bottom 85 wall of an aperture 90.

49 designates an arm, the construction of which varies in accordance with the type of grate employed. The free end of such arm is provided with a bulged or outwardly depressed portion, which forms a shield or cover for the portion of the grate which is adapted to receive the shaker bar, while its opposite end is mounted on a shaft 50, which passes through an aperture 51 in the plate 90 95 33, and has its opposite end journaled in one of the apertures 52 in the rear plate of the stove.

53 designates a link, see Fig. 4, provided with a plurality of apertures 54 adapted to 100 receive a pin 55, which latter also passes through one end of a link 56, the other end of said link being secured to the arm 57 of a damper 58, by means of a pin 59, passing through one of the apertures 60 in said arm. 105 In Fig. 4, a right hand arrangement of the parts is shown, while in Fig. 12, a left hand arrangement of such parts is shown, and at each side of the rear plate 5 is located a lug 61, which limits the movement of the 110 damper 58 in one direction, and the damper is normally maintained closed and its adjuncts maintained in normal position by means of the weight of the parts, and by means of a spring 62, mounted in any desired manner, but shown for purposes of illustration, and having one end secured to an extension from the arm 57, and its other end to a fixed point on the stove. The smoke-pipe 22 communicates with two dust 115 passages 63 provided with openings 64, controlled by a damper 58, it being understood that by such construction, a right or left hand arrangement of the dust dampers may be provided, and that when one of the 120 openings 64 is not in use, it will be closed by means of a suitable cover.

It will be seen that when the shaker-bar is

applied to the grate to actuate the same, the arm 49 will be raised, thereby rocking the shaft 50 and causing the dust damper 58 to move into open position, so that whenever 5 the grate is shaken, the ash pit is in direct communication with the stove-pipe. 65 designates a shelf having apertured flanges 66, see Figs. 8 and 9, which are adapted to interlock with the lugs or catches 14, and said 10 shelf has a portion thereof depressed, as at 67, and is provided with lugs 68, which form a support for a cover 69. The purpose of this depressed portion 67 is to form a chamber adapted to receive the descriptive matter 15 illustrating and describing the various parts of the stove and also instructions for operating the stove and ordering repair parts, and the manner in which the parts of the stove are assembled, so that such matter is 20 always instantly available and not likely to be lost.

The front plate 4 is provided with an upper rib 70 and a lower rib 71, having the same conformation, in order that the front 25 plate may be reversed in a manner which will hereinafter be described.

The fire end of stoves or "ranges" of this character, as heretofore constructed, has been made in either a one piece casting or in 30 two pieces. When the fire end has been made in two pieces the portion of the casting directly opposite to the fire has always been made in the form of a loose oblong plate somewhat larger than the water front and 35 bolted to the end casting. It is customary to have as many of these loose sections or plates as there are taps for the water front. In other words, a separate plate for each set of inlet and outlet holes of the water front. 40 The plates of course contain holes to correspond with the holes of the water front. When the end casting is made in one piece, holes are provided in the casting to suit the particular water front to be used. In either 45 case the pipes connected to the water front pass through a casting that is not an integral part of the water front.

This method is very unsatisfactory in practice in several particulars. As heretofore made, water fronts have not usually 50 been an integral part of the stove but have usually been made in block form of suitable size or shape for the fire box in which they were used, and have been retained in position 55 by a loose top clamp together with a grate or bricks at the two ends of the fire chamber. These bricks and grate referred to being loosely fitted allow much lateral movement of the water front, and thereby permit 60 ashes to lodge between the fire end of the stove casting and the water front. Every movement of the fire or jarring of the stove causes the ashes and dust to leak out around the pipes of the water front. While

this has been the cause of much complaint, it 65 is not the worst evil resulting from this method of making and installing a water front. Where stoves are connected to the chimney and the water back or water front subsequently installed which is an invariable custom, the pipes are very often cut a fraction of an inch too long and when so used the water front is forced inwardly and laterally from the fire end casting toward the fire, which not only permits leakage of 70 ashes and dust as stated, but permits the passage of air to the top of the fire, thereby checking the draft, and rendering it impossible to produce the best results.

Water fronts as now made are formed 80 with a rough surface and do not make an air tight fit against the fire-end casting as they should do to insure freedom from dust and prevent leakage of air into the top of the fire chamber. My present invention insures 85 against and overcomes the above noted defects, by reason of its integral form. The pipes enter the water front direct, not first through a fire end casting and then into the water front. In my present invention the 90 water front becomes an integral and fixed part of the stove, as distinctly fixed as its back, bottom or sides.

Referring now more particularly to Figs. 4, 14 and 15, 72 designates my novel panel 95 water back which is adapted to cover the aperture 73 in the end casting 2, and is provided with the slotted ears 74 whereby it may be rigidly fixed to the end casting 2 by means of fastening devices 75. The hot and 100 cold water pipes 76 and 77 respectively may be connected in different ways with respect to the water jacket and, as here shown, they are connected with an end of the water jacket although they may be connected at 105 the points indicated by dotted lines at 78, 79, 80 and 81, or in various other positions, it being understood that the hot water pipe would be connected at 78 or 80, and the cold water pipe at 79 or 81. The water jacket 72 110 is provided with lugs 82 which seat in the angle bars 83, and the top and bottom are each provided with such lugs in order that the water jacket may be reversed if desired. One end of the water jacket has a lug 84 115 which forms a seat for the fire brick and the other end of the water jacket is provided with a flange 85 to support a fire brick and a recess 86 with which the fire brick will interlock. The plate 87 forming one side of 120 the oven is extended to seat in one of the lugs 88, so that the oven can be assembled with the plate 1 to form either a right hand or left hand arrangement of the oven.

It will be apparent from the foregoing 125 that the front plate with the doors may be bodily reversed to coöperate with either a right or left hand oven arrangement. The

castings forming the oven and the fire chamber and their adjuncts are not reversed but are simply shifted from right to left in accordance with whether a right or left handed arrangement of the oven door is desired. The plate 4 is simply turned upside down. The shank plate is not reversed, but is simply moved to the proper position at the right or left hand side of the plate and secured to it. The dust damper and its adjuncts can be assembled at either end of the stove in accordance with the arrangement of the fire chamber and ash pit. The grate mechanism and end plates of the stove may also be transferred from one side to the other of the stove.

The arm 49 terminates adjacent the portion of the grate which receives the shaking implement and may be located within or exteriorly of the stove, it being understood that its location will vary in accordance with the type of grate employed and that it is only essential that the arm extend in such a manner that it will be actuated when a shaking implement is connected with the grate.

It will now be apparent that I have devised a novel and useful stove, which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. A stove having a front plate provided with an oven door and superposed doors at one side thereof, said plate having the same conformation on its top as on its bottom whereby the oven door is adapted without being disconnected from said front plate and without change to be reversed for a right or left arrangement of stove, the upper of said superposed doors forming without being disconnected from said front plate the fire chamber door with a left arrangement of the stove and the ash pit door with a right arrangement of stove, and the lower of said superposed doors forming with a left arrangement of the stove the ash pit door and with a right arrangement of the stove the fire chamber door.

2. A stove front plate having the same conformation at its top as at its bottom and provided with an oven opening, a fire chamber opening and an ash pit opening, doors movably carried by said plate and covering said openings and adapted to serve without

being disconnected from said front plate for a right or left hand arrangement of the stove, catches on said plate, and means carried by each door to interlock with its respective catch when said plate is arranged for either a left or a right hand arrangement of the stove part.

3. A stove front plate having the same conformation at its top as at its bottom and provided with an oven opening, a fire chamber opening and an ash pit opening, doors movably carried by said plate and covering said openings and adapted to serve without being disconnected from said front plate for a right or left hand arrangement of the stove, catches on said front plate, means carried by each door to interlock with the same catch when said plate is arranged for either a left or a right hand arrangement of the stove part, cleaning openings on opposite sides of said oven door opening, and removable covers for said cleaning openings.

4. A stove front plate having an oven door opening, and an opening at a side thereof, a shank plate located centrally of said side opening, to form a fire chamber opening and an ash pit opening, the top and bottom wall of said side opening being outwardly deflected, upper and lower doors covering said openings, catches on said upper and lower doors, and said plate having openings the walls of which interlock with the catches of said upper and lower doors when said plate is arranged for a left hand arrangement of a stove and also when said plate is bodily reversed for a right hand arrangement of a stove.

5. The combination with the end plate of a stove having an opening therethrough, of a water back consisting of a casting having its water chamber located substantially inwardly of said plate and having a panel projecting through said opening to form a continuation of said end plate, and the top and bottom of said water back having lugs on its top and bottom and having its top and bottom of the same conformation whereby the water back may be reversed.

6. The combination with the end plate of a stove having an opening, of a water back consisting of an integral casting fixed to said end plate, and having the fire brick supporting lugs 84 and 85 at the ends, and the fire brick interlocking recess 86, and the lugs 82 on its top and bottom, the water chamber of said water back being substantially inwardly of said end plate and said water jacket having a panel extending into said opening and forming a continuation of said end plate.

7. A stove, having a plurality of dust passages, and provided with a front plate having an oven door and superposed doors at a

side thereof, the top and bottom of said front plate having the same conformation whereby the oven door is adapted for both right or left hand arrangement of the stove, the upper of said superposed doors forming a fire chamber with a left hand arrangement of the stove and forming the ash pit door with a right hand arrangement of the stove,

and said stove having an ash pit communicating with one or the other of said dust 10 passages in accordance with its arrangement for a right or a left hand stove.
